UNITED STATES PATENT OFFICE.

JOHN ROY STARK, OF RACINE, WISCONSIN, ASSIGNOR TO THE WEBSTER ELECTRIC COMPANY, OF RACINE, WISCONSIN, A CORPORATION OF WEST VIRGINIA.

HIGH-TENSION MAGNETO.

1,240,615.

Specification of Letters Patent. Patented Sept. 18, 1917.

Application filed June 26, 1916. Serial No. 105,802.

To all whom it may concern:

Be it known that I, JOHN ROY STARK, a citizen of the United States, residing at Racine, in the county of Racine and State 5 of Wisconsin, have invented certain new and useful Improvements in High-Tension Magnetos, of which the following is a full, clear, concise, and exact description, reference being had to the accompanying drawings, forming a part of this specification.

My invention relates to high tension magnetos of the type employed for ignition purposes in connection with internal combustion engines. The object of my present 15 invention is to provide novel means for preventing premature and improper firing, said means being incorporated in a novel magneto machine wherein the usual distributor and its driving gear are eliminated.

20 In the accompanying drawings illustrating my invention,

Figure 1 is a vertical axial sectional view of my improved magneto machine;

Fig. 2 is a transverse sectional view taken 25 on the line 2—2 of Fig. 1 and looking in the direction indicated by the arrows;

Fig. 3 is a fragmentary sectional view of the armature structure, taken on the line 3—3 of Fig. 1, and looking in the direction indicated by the arrows;

Fig. 4 is a detailed view in cross section of one of the collector rings taken on the line 4—4 of Fig. 1 and looking in the direction indicated by the arrows, and

35 Figs. 5, 6, 7 and 8 are diagrammatic views showing the positions of the several parts during different cycles when my invention is applied to a four cylinder four cycle internal combustion engine.

40 Similar characters of reference refer to similar parts throughout the several views.

In the drawings 10 indicates the permanent magnets which are provided with the usual pole pieces (not shown) and which are mounted upon a base 11 which 45 may be formed as a separate piece or integral with a horizontal and generally cylindrical housing or body portion 12. At 13 is illustrated the armature which bears in the ends of the housing 12 and may be provided with ball bearings if desired, although in the accompanying drawings I have illustrated ordinary oil bearings. One end of the primary winding 14 is grounded to the

55 armature core and body and one member of a suitable primary contact breaker 15 carried at one end of the armature shaft, while the other end of the primary winding is connected with the other member of the contact breaker in the usual manner. The 60 condenser which is conveniently carried with the armature structure is illustrated at 17 and is connected in the primary circuit in a manner well known to those skilled 65 in the art.

The parts thus far described form no essential part of my present invention and may be of any suitable or well known construction, although I prefer that the armature structure *per se* shall be of the construction illustrated in Figs. 1 and 2, wherein the primary winding 14 and the secondary winding 18 are mounted upon and carried by a suitable laminated core 19, which is disposed between the brass end plates 20 and 21, the ends of the core being retained in position between the ends of arcuated plates 22—22 extending between the ends of the core 19 and the end plates 20 and 21.

20 23 and 24 indicate a pair of collector 70 rings which are preferably formed integral and of insulating material and which are fixed to rotate with the armature structure. The collector ring 23 is provided with a contact segment 23^a, and the collector ring 24 is provided with a contact segment 24^a. The insulation which constitutes the collector rings and carries the contact segments 23^a and 24^a is conveniently provided with 75 a pair of integral bosses 25—25 which extend through apertures in the adjacent armature end plate 21. The secondary armature winding 18 has its opposite ends connected to the collector segments 23^a and 24^a, as is clearly shown in Fig. 1 and Figs. 80 5 to 8 inclusive. It will be noted that the collector rings 23^a and 24^a are disposed on opposite sides of the collector ring structure, and that each of the collector segments 85 extends around its associated collector ring 100 in an arc of a little more than 180 degrees.

Reference letters A, B, C and D indicate 105 collecting brushes conveniently carried by the body portion or housing 12 of the magneto, and which are arranged in pairs on diametrically opposite sides of the collector rings 23 and 24, the brushes A and C being adapted to alternately contact with the seg-

ment 23^a, and the brushes B and D with the segment 24^a. Having bearings in the magneto housing 12 and disposed above the armature shaft is 5 a shaft 26 provided with a gear 27 meshing with a gear 28 fixed upon the armature shaft, the relation of the gears being such that the shaft 26 is driven with and from the armature shaft at a speed one-half the 10 speed of the armature shaft. The shaft 26 similarly to the armature shaft has been illustrated as provided with plain oil bearings, although ball bearing may, of course, be employed, if desired. Carried by the 15 shaft 26 are a pair of electricity conducting sectors 23^b and 24^b. It is to be understood that the shaft 26 as well as the sectors 23^b and 24^b are of electricity conducting material and that therefore when either one of 20 the sectors lies opposite one of the collector segments that segment is grounded to the magneto housing 12 through the shaft 26. The magneto is so mounted that its housing 12 is grounded to the frame of the associated 25 engine, in order that the operation hereinafter to be described may occur. In order to prevent sparking at the points where the shaft 26 is journaled, a spring pressed plunger 29 carried by the housing 12 presses 30 against the gear 27, it being understood that both the gear 27 and the plunger 29 are of electricity conducting material.

Referring now to the embodiment of my invention illustrated in Figs. 5 to 8, the cylinders of the four cycle internal combustion engine are provided with the ordinary spark plugs illustrated at 30, 31, 32 and 33. The collecting brushes on one side of the collector ring structure, we may say the brushes 35 A and B, are connected with the spark plugs of the cylinders A' and B', while the brushes C and D, which are located on the other side of the collector ring structure, are connected with the spark plugs of the cylinders C' 40 and D'.

In the operation of the magneto when the pistons in the cylinders A' and D' are at the upper end of their strokes, the pistons of the intermediate cylinders B' and C' are 50 at the lower end of their strokes as shown in Fig. 5. In the example shown the combustible mixture in the cylinder A' has just been compressed and is being ignited. The piston in the cylinder B' is beginning its 55 exhaust stroke, the piston in cylinder C' is beginning its compression stroke and the piston in cylinder D' is at the end of its exhaust stroke. When the parts are in the position just described the collector segments 60 23^a and 24^a contact with the brushes A and D, and the grounding sector 24^b lies adjacent one end of the collector segment 24^a. With the parts in these positions the secondary circuit is closed through collector 65 segment 23^a, brush A, to spark plug 30, and

thence to ground and from ground through the grounding sector 24^b to segment 24^a, and thence to the secondary winding 18. Were the grounding sectors not provided the secondary current would have found a path 70 through the spark plug 33 and thence back to the secondary winding 18 through the brush D and collector segment 24^a, and a useless spark would occur at the plug 33, inasmuch as the piston in the cylinder D' is on 75 its exhaust stroke. It will be understood that the grounding sector 24^b need not necessarily make perfect contact with the segment 24^a, the only requirement being that the path through the sector 24^b and segment 24^a be 80 of less resistance than the gap at the spark plug 33. It will thus be seen that although the spark plugs are connected in pairs, the plugs 30 and 33 constituting one pair and the plugs 31 and 32 constituting the other 85 pair, whenever a spark occurs in the plug 30 the occurrence of a spark at the plug 33 is prevented, due to the presence of the grounding sector 24^b. After a complete rotation of the engine crank shaft and magneto armature the collector segments reach the positions illustrated in Fig. 7, the piston of cylinder A' being this time at the end of its exhaust stroke, the piston of cylinder D' at the end of its compression stroke 90 and the collector segments in the same positions as shown in Fig. 5. However, due to the fact that the shaft 26 which carries the grounding sectors travels at half armature speed the sector 23^b this time lies adjacent 95 the collector segment 23^a, and the grounding sector 24^b lies away from the segment 24^a. In this case the secondary circuit is closed through segment 24^a, brush D, and plug 33 to ground, and thence through shaft 26, 100 grounding sector 23^b, and collector segment 23 to the secondary winding 18.

The same action takes place at the paired intermediate cylinders B' and C' as has been described in connection with the cylinders 105 A' and D', that is, whenever one of the cylinders B' or C' is in condition to have its compressed charge fired circuit connections are established which tend to create sparks at both of the plugs 31 and 32, but the 110 grounding sectors operate to prevent the passing of a spark at the plug not to be fired.

By the improvement herein shown and described the customary distributor and the gearing between it and the armature shaft 115 are dispensed with, thus materially simplifying the construction of the magneto and reducing the cost of its manufacture. Moreover, means is provided to absolutely prevent sparking at the plugs of cylinders not 120 to be fired.

The construction of my improved magneto enables me to make use of comparatively long collector segments, thus minimizing 125 sparking at the collector segments. More- 130

over, the armature of my improved magneto machine may be driven in either a clockwise or a counter clockwise direction without reversing the collector rings or changing their position.

Having thus described my invention what I claim as new and desire to secure by Letters Patent of the United States, is:

1. In a high tension magneto the combination with a rotatable armature, a pair of collector rings movable with the armature, each of said collector rings provided with a contact segment, said segments being connected in circuit with the secondary coil of the armature, a pair of brushes coöperating with each collector ring and a pair of grounding members coöperating with said collector rings and driven in timed relation thereto.

2. In an ignition magneto having primary and secondary windings, a rotary armature, a pair of collector rings movable with the armature, each collector ring having a contact segment, said segments being connected in circuit with the secondary winding, a pair of brushes coöperating with each collector ring and a pair of grounding devices, one coöperating with each of said collector rings.

3. In combination with the rotary armature of a high tension magneto, collector rings rotatable with the armature, each collector ring having a contact segment in circuit with the secondary winding of the magneto, a pair of brushes coöperating with each collector ring, an internal combustion engine having a plurality of spark gaps connected in circuit with said brushes, a shaft driven in timed relation to said armature and grounding devices, one for each segment, carried by said shaft.

4. The combination with the rotary armature of a high tension magneto, a pair of contact segments rotatable with the armature, a pair of brushes arranged to be engaged by each of said contact segments as the latter are rotated, means for connecting the segments in circuit with the secondary winding of the magneto and the brushes in circuit with the spark gaps of an internal combustion engine, a pair of grounding sectors coöperating with said contact segments and means for driving said grounding sectors in timed relation to the armature and contact segments.

5. The combination with the rotary armature of a high tension magneto, a pair of contact segments rotatable with the armature, said segments being connected in circuit with the secondary armature coil, a pair of brushes arranged to coöperate with each contact segment as the segment is rotated, an internal combustion engine having a plurality of spark plugs associated in pairs and electrically connected by the engine

frame, the plugs of each pair being connected in circuit with a diagonally opposite set of said brushes to alternately spark said pairs of spark plugs, and means for periodically grounding each of said contact segments to the engine frame.

6. The combination with the rotary armature of a high tension magneto, two collector rings rotatable therewith and each having a contact segment, said segments being connected in circuit with the secondary coil of the armature and the segment of one collector ring being arranged on the opposite side from the segment of the other collector ring, a pair of diametrically opposite brushes coöperating with each collector ring, an internal combustion engine having spark plugs associated in pairs, each pair of said plugs being connected in series with the brush on one side of one collector ring and the brush on the opposite side of the other collector ring, and means for periodically grounding said collector segments.

7. In combination with the rotary armature of a high tension magneto, a pair of collector rings rotatable with the armature, a contact segment for each collector ring, means for connecting the contact segments in circuit with the secondary armature coil, a pair of brushes for each collector ring, a shaft disposed adjacent said collector rings and driven with the armature, and means carried by said shaft for periodically grounding said contact segments.

8. In combination with the rotary armature of a high tension magneto, a pair of collector rings rotatable with the armature, oppositely disposed contact segments, one for each collector ring, means connecting each segment in circuit with the secondary armature coil, a pair of diametrically opposite brushes for each collector ring, a shaft adjacent said collector rings, means for driving said shaft from the armature in a relation of two to one, and grounding sectors carried by the said shaft arranged to coöperate with said contact segments.

9. In combination with an ignition magneto having primary and secondary windings, a pair of collector rings driven with the magneto rotor, a contact segment for each collector ring, a pair of brushes for each collector ring, means for connecting the contact segments in circuit with the secondary winding, a pair of oppositely disposed brushes for each collector ring, and a pair of grounding sectors driven in timed relation to the rotor and arranged periodically to coöperate with said contact segments.

10. In an ignition magneto having primary and secondary windings, a pair of collector rings driven with the magneto rotor, a contact segment for each collector ring, means for connecting the contact segments

in circuit with the secondary winding, a pair of brushes for each collector ring, a shaft in proximity to said collector rings and driven therewith in the relation of two to one, and grounding sectors carried by said shaft arranged to coöperate with said contact segments.

In witness whereof, I hereunto subscribe my name this 22 day of June, A. D. 1916.

JOHN ROY STARK.
